SHELDON CARY, OF NEW YORK, N. Y., ASSIGNOR TO CARY MANUFACTURING COMPANY, OF NEW YORK, N. Y., A CORPORATION OF NEW YORK.

BALE-TIE.

No. 903,128.

Specification of Letters Patent.

Patented Nov. 3, 1908.

Application filed May 6, 1904. Serial No. 206,614.

To all whom it may concern:

Be it known that I, SHELDON CARY, a citizen of the United States, residing in New York, borough of Brooklyn, in the county 5 of Kings and State of New York, have invented a new and useful Bale-Tie, of which the following is a specification.

My invention relates to an improved bale tie for use particularly on bolts or rolls of 10 cloth, though it will be obvious that it is adapted for various other similar uses.

The bale tie is so constructed that when the two members constituting the buckle of the tie are used in conjunction with the band 15 they exert a wedging action on each other, thereby being forced together facially. In this way said members exert a gripping action on each other and enable the tie to be drawn very tautly around the bale and held 20 securely in place.

My new tie is simple in construction, easy to make, readily applied to the bale, and, in practice, has proven of great utility.

The invention will be understood from 25 the following detailed description thereof, taken in conjunction with the accompanying drawings, wherein

Figure 1 is a view of the entire tie; Fig. 2 is a vertical section thereof on line 2—2 Fig. 30 1, showing the parts relieved from tension; Fig. 3 is a sectional elevation on the same plane as Fig. 2, showing the parts under tension; Figs. 4 and 5 show the two members constituting the buckle, and Fig. 6 shows 35 a modified form of the invention wherein one member of the buckle is constructed in the form of a wedge. Fig. 7 is a transverse view partly in cross section of the modified construction shown in Fig. 6 illustrating the 40 manner of attaching the ends of the band to the buckle members.

Similar letters refer to similar parts throughout the several views.

The buckle is composed of two members 45 A and B. The member A in its preferred form is made substantially rectangular in shape and is provided with a slot 5, through which the tie band is adapted to pass. The member B is provided with a similar slot 6, 50 for the same purpose. One side of member B is cut out centrally thereof, so as to leave a reentrant part 7, on either side of which the metal is bent upon itself to form lugs or jaws 8 and 9 the space between the lugs or

jaws forming a passage 13 for the end portion of the band, as hereinafter described. In the form of the invention shown in Figs. 1 to 5, the members A, B, are preferably stamped up from thin strip steel though it is apparent that they might be made in other 60 ways.

In the drawings the ends of the band are numbered respectively 10 and 11. In assembling the tie the end 10 is passed over the top of the member B, and then bent 65 upon itself around the reentrant part 7 and passed outwardly through the slot 6. The end 11 is passed through the passage 13 and beneath member A, then bent upon itself and passed through the slot 5 therein. A 70 band of the right length for the purpose intended having been provided, it is slipped around the bale, while the latter is under pressure in the baling press, and member A is placed in proper position so as to rest with 75 one edge within the angular part of member B. The pressure upon the bale is then relieved, whereupon the natural expansion of the bale produces a tension on the band. The effect of this tension is to cause the 80 members A and B to exert a wedging action upon each other and to bring them into the lapping relation shown in Fig. 3. In the construction described the greater the tension on the band, the greater is the wedging 85 action of the coupling members and as a result the tie is held very firmly and securely in place.

In the modified form of my invention shown in Fig. 6, I provide two buckle members A' and B', corresponding to the members A and B in the first form described. Member B' differs from member B in that it has not cut away portion 7, but is bent upon itself, and has an additional slot 12 at 90 the angle of the bend forming a passage for the band. The member A' differs from the member A in that it has no slot, but is made preferably solid and of tapering form resembling a wedge. If desired, member A' 100 may be made of wood or similar material instead of metal. In attaching the band to member B', the end of the band is first passed through the slot in the angle of the band, it is then bent upon itself and passed 105 through the second slot 6' therein, corresponding to the slot 6 in the member B. The other end of the band is wrapped around

2
member A' and drawn over upon itself and said member A' is then inserted in the angular part of member B'.

In using the second form of the invention 5 one end of the band is attached to member B', in the manner indicated, and the other end placed around the bale, while the latter is under tension in the press, and said latter end is then connected with member A', 10 as indicated, and this latter member allowed to slip into the angular part of member B'. When pressure is relieved from the bale, the tension on the band, caused by the tendency 15 of the bale to expand, produces the same wedging action between members A' and B' as is produced between members A and B.

It will be observed that in both forms of the invention each end of the band is securely fastened to its buckle member and 20 that when the parts are placed under tension the ends of the bands, owing to the form of the buckle members, are brought intolapping and frictional relation, resulting in a very secure tie.

25 Having described my invention, what I claim as new and desire to secure by Letters Patent is:—

1. In an article of the class described, a coupling member provided with a down 30 turned portion and a band clamping surface, said member being provided with a slot adapted to receive the end of a band, a second coupling member to which the end of a band is adapted to be secured, the said second member having a band clamping surface, and an edge adapted to rest within the 35 down turned portion of the first member, so that when tension is exerted upon the band the said members are brought into co-operative relation with each other and a wedging action exerted upon the coupling members and a clamping action upon the band.

2. A bale tie consisting of two members 40 having opposing clamping faces, said members being provided with means for wedging them together so as to bring said faces into clamping positions as the members approach each other, each of said members being provided with a slot whereby the end portions 45 of a band may be respectively connected with said members by first passing a band between them, and then around the end of one member, and then back and through said slot, and again between said members.

55 3. A bale tie consisting of two members having opposing clamping faces, one of said members also having an inclined turned over end for receiving and wedgingly engaging the other member, and each of said members 60 being provided with a transverse slot, and said turned over end being provided with a

passage therethrough whereby the end portions of a band may be respectively connected with said members by first passing the band between them and then around the 65 end of one member, and then back and through said slot and again between said members, one of said end portions also passing through the passage of said turned over end.

4. In an article of the class described, a buckle composed of two members, one of said members being provided with lugs forming a wedge shaped socket and with a slot adapted to receive the end of a band, 75 the second member also being provided with a slot adapted to receive the end of a band, said second member being adapted to rest on the face of the first member, with one of its edges between said faces and aforesaid lugs, 80 and in wedging engagement therewith, the said parts so co-operating that when tension is placed upon the band the buckle members exert a wedging action upon each other and a clamping action upon the band.

85 5. In an article of the class described, a member having one edge thereof bent towards itself so as to form an angle, means for attaching a band to said member, a second member adapted to rest within the angle of the first member, means for attaching a band to said second member, the co-operative relation between the said members being such that when tension is placed upon the band said members exert a wedging action 95 on each other and a clamping action on the band.

6. In an article of the class described, a coupling member provided with a down turned portion, said member being provided 100 with a slot, the end of a band passing over the face of said member and bent upon itself and extending through the slot in said member, a second coupling member provided with a slot, the end of a band passing over 105 the lower face of said member, said band being also bent upon itself, the said second member having one edge adapted to rest within the down turned portion of the first member so that when tension is exerted 110 upon the band the said members are brought into co-operative relation with each other and a wedging action exerted upon the members and the band.

115 In testimony whereof I have signed my name to this specification in the presence of two subscribing witnesses.

SHELDON CARY.
